UNITED STATES PATENT OFFICE

2,195,413

WOOD PRESERVATIVE OIL

Jacquelin E. Harvey, Jr., Atlanta, Ga.

No Drawing. Application October 22, 1937,
Serial No. 170,502

2 Claims. (Cl. 134—78.6)

The invention relates to creosote-coal tar oil valuable as a wood preservative, paving oil, roofing material, waterproofing material and the like. Coal tar alone may be used for wood impregnation but has features which are very objectionable in some situations, such as bleeding, dark color, and high temperatures required to reduce viscosity during impregnation. To avoid the difficulty it is the practice to impregnate wood for some uses with a mixture of creosote and coal tar. The percentage most used is called an 80—20 oil i. e., 80% creosote and 20% oil.

It is an object of the invention to provide a process for producing a creosote-coal tar oil of any desired percentages: to produce an oil of the desired percentages from coal tar with substantially volume for volume conversion: to produce creosote-coal tar oils having no more residue than is permissible under any certain specifications: to produce oils comparable to creosote-coal tar oil of varying percentages from starting materials other than coal tar as for instance any tars or residues of tars recovered from coal, wood or the sap of trees. By residue in this description and in the appended claims is meant the bottoms remaining from the removal, as by distillation, of any commercial fraction from the starting material above named.

By practice of the present invention a wood preservative may be produced falling within the trade specifications at present controlling as a standard.

Such specifications in force are as follows:

The solution shall be a coal tar product of which at least 80% shall be of coal-gas tar or coke oven tar, and the remainder shall be refined or filtered coal-gas tar or coke-oven tar. It shall comply with the following requirements: It shall not contain more than 3% water; it shall not contain more than 2% of matter insoluble in benzol; the specific gravity of the solution at 38° C. compared with water at 15.5° C. shall not be less than 1.05 or more than 1.12; the distillate, on a water-free basis, shall be within the following limits: Up to 210° C., not more than 5%; up to 235° C., not more than 25%; the solution shall yield not more than 6% coke residue. The specifications above quoted are set forth for purpose of illustration only. As already stated, the product of applicant's invention may be made to meet the present trade specifications or any changed specifications that may from time to time be extant.

When producing an oil of the creosote-coal tar type by first stripping a light oil from any of

the tars named, hydrogenating the residue to a point such that when blended with the first recovered light oil the desired oil will result, it results in the case of some of the tars that there is an inadmissible percentage of free carbon, coke residue and/or insolubles in benzol.

To remove a sufficient percentage and no more of said residue, in accordance with the present invention, the percentage of said residue in the hydrogenated material is determined, and also the excess percentage of the residue. An amount of the hydrogenated material which will carry the portion of the residue corresponding to said excess percentage is separated and evaporated to dryness, the distillate is condensed and blended with the remaining hydrogenated material and with the light oil first removed, to produce the oil of the creosote-coal tar type oil having the permissible residue and no more. The residue from the evaporation-to-dryness step is discarded so far as the process of the invention is concerned.

It is possible by the procedure above described to produce an oil comparable with an 80—20 oil, a 70—30, 50—50, 10—90, or any other percentage of creosote and oil.

A feature of the invention has to do with paving and roofing material by reason of the discovery that hydrogenation of pitch reduces the range of variation of penetration with changes of temperature. One type of paving material is "priming" oil which is liquid at atmospheric temperature when applied to a base of broken stone, natural sub-soil, or the like, and becomes a solid upon "curing", to provide a water excluding diaphragm. For this use a hydrogenated pitch may if desired be blended with a relatively small percentage of creosote—either natural or synthetic—when the normally liquid oil resulting from the blend will cure as usual but will not so readily become brittle when cold.

For use as a binder—either hot or "cut back" and as a stone coating or for use by penetration, a hydrogenated pitch, brought to the desired penetration at the highest expected atmospheric temperature, will be found to not have the usual low penetration under winter conditions.

Many consumers of wood preservatives, such as creosote, creosote-coal tar solution, or the like, have private specifications for the preservative they use. My process is so flexible in supplying any nature of end products, that the following examples are cited:

Example 1.—Any of the pitches are hydrogenated at from 100°—500° C., 100—300 atmos-

phers partial hydrogen pressure, with or without catalyst or catalysts, and for such a length of time that samples withdrawn and tested show that said hydrogenated pitch when blended with 5 desired percentage of synthetic creosote as described in my Patent No. 2,082,885, will substantially meet the specification of the desired creosote coal tar solution.

Example 2.—In the production of an oil substantially meeting the specification of any desired 10 nature of a creosote-coal tar solution, wherein the desired percentage of synthetic creosote is blended with necessary percentage of natural coal tar to produce the specifications, control 15 over free carbon, coke residue, insoluble in benzol, etc., may be had by selection of the starting material, that is, (1) the synthetic creosote and (2) the natural coal tar.

Example 3.—In the production of an oil of 20 the creosote-coal tar solution type; using coal tar as a starting material, the tar is charged to a reaction chamber and hydrogenated under temperature of 100°-500° C., 100-300 atmospheres partial hydrogen pressure, with or without 25 catalyst or catalysts, and for such a time that samples withdrawn indicate that the desired oil has been formed, as for instance an oil equal or similar to an 80-20, 70-30, 60-40, 50-50, etc. creosote-coal tar solution.

30 In the practice of this form of the invention, and when using certain tars for conversion to, say an oil similar to a 50-50, at times it is found that even though the desired distillation range 35 has been induced, the free carbon, coke residue and insoluble in benzol are too high; these percentages of mentioned objectionables may be reduced as mentioned supra, or the hydrogen partial pressure may be raised, which has the effect of reducing said coke residue, etc.

40 *Example 4.*—A pitch, as for instance a coal tar pitch, is hydrogenated under hydrogenating conditions of 100°-500° C., temperature 100-300 atmospheres partial hydrogen pressure, with or without catalyst or catalysts, and for such a 45 length of time that samples withdrawn indicate that when said hydrogenated pitch is blended with desired percentage of synthetic creosote, an oil comparable to a creosote-coal tar solution is formed. By control of hydrogenation of said 50 pitch and/or nature of synthetic creosote and/or percentage of said hydrogenated pitch and said synthetic creosote used in said blend to form the oil comparable to a creosote-coal tar solution, an oil of any desired specification may be made.

55 *Example 5.*—The production of a wood impregnant, as for instance of the creosote-coal tar solution type, wherein synthetic creosote is blended with natural pitch to produce an oil 60 highly desirable as a wood preservative because of its higher toxic value than a wood preserving oil of like type made from coal tar under present accepted conventional manufacturing conditions, and of comparable boiling range, may be carried 65 out as follows:

A synthetic creosote as described in my Patent 70 No. 2,082,885, is produced and blended with the necessary percentage of natural pitch as in Examples 5 and 6, or with coal tar as in Example 2, 75 to form an oil comparable to the creosote-coal tar solution desired or natural creosote is blended with the synthetic creosote as in Example 6 below.

The synthetic creosote as disclosed in my 75 patent referred to has less than 10% boiling be-

low 210° C. and not less than 50% boiling below 355° C.

Great benefits will accrue from the above form of the invention, for the use of said pitch as a component part of said wood preservative 5 will remove from an already glutted market, a definite and large percentage of said distress pitch.

Also, the blending of the synthetic creosote with said natural pitch, does not result in a deficiency in toxic value, as might be expected because of the presence of the pitch, for the reason that said synthetic creosote has a toxic value of such high order as to compensate for the absence or low value of toxicity in said pitch. 15

Example 6.—Still another important variation resides in the production of a wood preservative of the creosote or creosote-coal tar solution type as follows:

A given coal tar, or the like, is relieved, as by 20 distillation, of at least a portion of its naturally present wood preservative, as for instance to an upper limit of 300° C. The resultant pitch is then hydrogenated under conditions, as for instance a temperature of 100°-500° C., hydrogen 25 partial pressure 100-300 atmospheres, with or without catalyst or catalysts, for such a time that samples withdrawn indicate that said hydrogenated pitch when blended with the first removed natural wood preservative will give an oil, 30 depending on percentages used, similar to a creosote or creosote-coal tar solution.

Example 7.—Another important and valuable 35 form of the invention resides in the use of a metallic halid, such as anhydrous aluminum chloride, as a decarbonizing catalyst.

In this instance, but not in the sense of a limitation of other useable starting materials, dry crude coal tar is charged to a suitable reaction chamber with from 1 to 10 percent of said metallic halid, as for instance, aluminum chloride. The contents of said reaction chamber are then heated to from 100°-500° C., while under agitated 40 conditions, and under self-generated pressure due to said heat, for such length of time that 45 when heat and agitation have been discontinued, a portion of the original tar charged to said reactor settles into substantially a heavy underlying mass which includes the halid, with a thinner and less viscous over-lying layer. This over-lying layer may be separated from the entire 50 mass in any desirable manner and used directly without further treatment or distillation as a wood preservative, or blended with any other known wood preservative to form a useful product. 55

The action of the metallic halid has seemingly the effect of subtracting carbon from a portion of said coal tar, and may be the cause, directly or indirectly, of the thinner and over-lying layer 60 mentioned. However, there may be reaction entering into the accomplished and noted results that I do not recognize, thus for convenience, I refer to the noted result as a de-carbonizing effect. 65

Instead of using autogenous pressure, as mentioned supra, pressure of extraneous source may be used, as for instance, hydrogen, any inert gas, or any hydrocarbon gas, with the added benefit in the case of hydrogen and the hydrocarbon 70 gases, that the hydrogen or hydrogen content thereof, may under known conditions enter into the reaction for results that are immediately apparent.

The example of using a metallic halid as a "de- 75

carbonizing catalyst," shall in no way be construed to limit the ability of said halid to promote or assist in the addition of hydrogen.

In the treatment of the heavy under-lying 5 layer including the halid, the halid may be removed from the mass by any known means which forms no part of the present invention, and the heavy mass ex halid used for any useful purpose, as for the instance the production of 10 synthetic creosote in known ways.

By the word "natural" describing a creosote or a coal tar oil or other oils as used herein and in the claims, is meant an oil derived by distillation of a tar.

15 I claim:

1. An oil of the wood preserving type comprising a mixture of from 10% to 90% of synthetic creosote produced by hydrogenation of

pitch or tar, boiling less than 10% at 210° C. and not less than 50% at 355° C. with from 90% to 10% of coal tar fractions boiling substantially completely above 200° C., said mixture boiling less than 10% at 210° C., and not less than 40% at 355° C. and having toxic properties in excess of those of a mixture of natural coal tar products of similar physical properties. 5

2. An oil of the wood preserving type comprising a mixture of from 10% to 90% of synthetic creosote produced by hydrogenation of pitch or tar, boiling less than 10% at 210° C. and not less than 50% below 355° C., with from 90% to 10% of coal tar, said mixture having toxic properties in excess of a mixture of natural creosote and coal tar with the same physical properties. 10 15
